UNITED STATES PATENT OFFICE.

JOHN MEHL, JR., OF JERSEY CITY, NEW JERSEY.

DESIGN FOR A COVER FOR POCKET-BOOKS OR CARD-CASES.

SPECIFICATION forming part of Design No. 28,172, dated January 18, 1898.

Application filed December 14, 1897. Serial No. 661,901. Term of patent 3½ years.

To all whom it may concern:

Be it known that I, JOHN MEHL, Jr., a citizen of the United States, residing at Jersey City, in the county of Hudson and State of New Jersey, have invented and produced a new and original Design for the Covers of Pocket-Books or Card-Cases, of which the following is a specification, reference being had to the accompanying drawings, forming a part thereof, in which—

Figure 1 is a plan view of a cover for a pocket-book or a card-case embodying the features of my design, and Fig. 2 is a transverse section on the line 2 2 of Fig. 1.

The leading feature of the design consists in the embossed corner-panels A and B, each

of which has two straight outer edges *a* and *a'* and an inner edge formed with two scallops *a*² and *a*³, the scallops meeting at the center of the panels.

A minor feature of the design consists in a bead-like edge *b* at the scalloped portions of the panels and in depressed lines *b'*, crossing the panels and extending to the point where the scallops of the panels meet.

I claim—
The design for the cover for pocket-books and card-cases herein shown and described.

JOHN MEHL, JR.
